UNITED STATES PATENT OFFICE.

OSCAR H. DAVIS, OF KANSAS CITY, MISSOURI.

SMOKING PIPE.

Application filed March 19, 1924. Serial No. 698,044.

To all whom it may concern:

Be it known that I, OSCAR H. DAVIS, a citizen of the United States, and a resident of Kansas City, county of Jackson, State of Missouri, have invented a certain new and useful Improvement in Smoking Pipes, and of which the following is a complete specification.

This invention relates to smoking pipes, and has for its prime object to produce a pipe for affording a cool smoke by providing for the separation, therefrom at an intermediate point of the stem, of all secretion of nicotine or moisture exuded from the tobacco in the bowl. A further object is to provide a pipe having a trap for collecting juice and nicotine secretions to prevent them reaching the mouthpiece of the stem, and from which such secretions can be readily discharged by blowing through the stem. A still further object is to provide the stem with a separable or intermediate section forming the trap mentioned, and a centralized smoke stream expander in said trap for subdividing the smoke stream and thereby more quickly cooling the smoke, and facilitate the deposits of juices and nicotine in the trap. Another object is to produce a pipe characterized as outlined, which is not increased appreciably or noticeably in weight over the standard type of pipe, which can be made economically, and which possesses the desirable qualities of durability and strength.

With these general objects in view, the invention consists in certain novel and useful features of construction and combinations of parts, as hereinafter described and claimed; and in order that it may be fully understood reference is to be had to the accompanying drawing, in which:

Figure 1 is a side elevation of a smoking pipe embodying the invention.

Figure 2 is a central vertical longitudinal section of the pipe on a magnified scale.

Figure 3 is a detail perspective view, on an enlarged scale, of the smoke stream expander of the pipe.

Figure 4 is a cross section on the line III-III of Figure 2.

Fig. 5 is an elevation of an extension tube which strengthens the connection of the stem with the bowl of the pipe and serves to keep the bowl and adjoining portion of the pipe dry and sanitary.

Referring now to the drawings in detail,

1 indicates the bowl and 2, 3 and 4 the sections of the stem, the part 2 being integral with the bowl, part 4 the customary mouthpiece, and part 3 the intermediate separable section.

Section 2 is provided with the customary small bore 5 leading to the socket 6, and the mouthpiece as usual is provided with the small bore 7, leading to the socket 8.

The separable or intermediate section is provided with a large bore 9, in alignment with the bores 5 and 7, and is diametrically reduced at 10 to engage the socket 6 and at 11 to engage the socket 8, it being understood that the joints between the section 3 and the other parts of the stem may be slip joints as shown, or may be threaded or equivalent joints.

At one end section 3, which is preferably of aluminum, is provided with a tubular extension 12 for fitting snugly in the bore 5 of the pipe, and said tubular extension serves to strengthen the pipe at the juncture of the bowl and stem, and also to collect gummy accumulations and the like which will be removed with the withdrawal of the section 3, and thus maintain the bowl and stem portion 2 in substantially dry and sanitary condition.

For convenience of manufacture and in cleaning the bore 9, the extension 12 may be made detachable from the section 3. It should however be so firmly attached to said section, that the withdrawal of the latter from the pipe stem section 2, will withdraw the extension 12 from said section and the bowl. The said extension if formed integral with part 3, can be readily and easily cleaned, but when the pipe is subjected to the ordinary cleaning action, namely by blowing through the stem or mouthpiece as hereinbefore mentioned, it is preferable that the extension be removable, as otherwise nicotine might accumulate against the shoulder formed by the junction of the small bore of the extension with the larger bore of section 3.

As shown, the extension is provided with a slightly tapered head 13 for wedging engagement in the section 3, and said head forms an abutment at one end for a smoke expander element 14. This expander element is preferably of rectangular form and provided at its ends with enlarged rectangular heads 15, which contact with the wall of bore 9, and is thus centralized within said

bore. One head 15 is adapted to bear against the inner end of the head 13 as explained, and the other head against the bottom of socket 8 of the mouthpiece, and said heads are provided with cut-away openings or notches 16 so that smoke drawn from the bowl may pass through extension 12, the adjacent notches 16 and be spread or expanded thereby to pass along the four sides of the corresponding head, and then pass through the bore 9 around the expander 14 and, in subdivided streams, pass the other head and through its notches 16 to the bore of the mouthpiece. It will be obvious that by thus subdividing the stream of smoke as it passes the two heads 15 successively, a better opportunity for the precipitation of nicotine and juices is given and the smoke therefore will reach the tongue in a cooler state and uncontaminated by nicotine which will accumulate around and upon the expander and within the bore 9.

After suitable intervals, the smoker can clean a pipe of this character sufficiently by simply disconnecting the mouthpiece and section 3 from the stem section 2, and blowing through the mouthpiece, this action having the effect of keeping the notches of the expander clear of obstructions. If it is desired to make this action more thorough, the extension 12, if removable, can be easily detached, and when it is desired to thoroughly clean the stem, the mouthpiece will also be removed so that the expander can be dropped out of the section 3 for scraping or washing, and to give better access to the bore of said section with a swab.

Through the protection afforded to the bore 5 by the extension 12, the bowl of the pipe will be kept comparatively dry and sanitary, as before explained, and this statement of course applies to the entire length of stem 2.

A pipe of the character outlined possesses the features of advantage set forth as desirable in the statement of the object of the invention, and it obviously can be modified in minor particulars without departing from the principle of construction and mode of operation involved, or the spirit and scope of the appended claims.

I claim:

1. In a smoking pipe, a stem having its bore of enlarged diameter between its points of communication with the bowl and the mouthpiece, and a smoke stream expander extending within the said enlargement and provided at its extremities with enlarged heads contacting at laterally-spaced points

with the wall of said enlargement of the bore to provide passages between the said heads and the wall of the stem and fitting at its ends over the portions of small diameter of the bore, the heads having projections to engage end walls of the stem and prevent the heads from closing the portions of small diameter of the bore; the said projections and the passages between the heads and enlarged portion of the bore permitting the smoke and juices to pass from the bore of the bowl end of the stem into the said enlargement, and the smoke to pass from the said enlargement into the bore of the mouthpiece. 75

2. In a smoking pipe, a stem having its bore of enlarged diameter between its points of communication with the bowl and the mouthpiece, and a smoke stream expander fitting within the said enlargement and at its ends over the constricted portions of the bore of the stem; the ends of the expander having notches to permit smoke and juices to pass from the bowl into the said enlargement and from the latter into the bore of the mouthpiece. 80

3. In a smoking pipe, a stem having a detachable intermediate section provided with a larger bore than and alined with the portions of the bore of the end sections, and a smoke expander fitting in the bore of the intermediate section, in alinement with the bores of the end sections, there being cut-away portions on the expander to cause the smoke from the bowl to enter the intermediate section in a plurality of streams, and to pass from said section to the mouthpiece in a plurality of streams. 90

4. In a smoking pipe, a stem having a detachable intermediate section provided with a bore of larger diameter than the end portions of the stem, and detachably secured to the latter; said intermediate portion having a tubular extension within the bore at the end of the stem adjoining the bowl, and a smoke expander fitting within the enlargement of the bore and provided with enlarged heads dividing said bore enlargement at each end into a plurality of passages; there being cut-away portions on the expander for establishing communication between the bore of the portion adjoining the bowl and the said enlargement, and for establishing communication between the latter and the bore of the mouthpiece of the stem. 105

In witness whereof I hereunto affix my signature.

OSCAR H. DAVIS.
